GAME APPARATUS

Francisco P. Gorospe, Wayne, Pa.

Application May 17, 1941, Serial No. 394,023

3 Claims. (Cl. 273—127)

The following is a detailed description of my novel game apparatus. This apparatus is designed to be used in a game where playing balls are propelled in the same manner as marbles toward an objective with the idea of having the balls come to rest in a cup or similar arrangement. The balls may be propelled by the fingers in the same manner as a marble would be propelled or in the alternative may be driven with a mallet, club or other device. The novel apparatus may be used alone or may be combined with others so that the game progresses from one objective to another, subject to suitable rules and penalties.

This objective serves not only as a cup or receptacle into which the balls fall but is provided with obstructions and other means serving to introduce hazards, difficulties or penalties. These features include a central vertical post in the cup serving to affect the travel of the playing ball by obstructing it or deflecting it. Another device introducing an uncertainty and hazard in the lodgment of the ball in the cup is a series of vanes. These vanes may repel the ball from the cup if the ball arrives with too great force. Where the ball fails to come to rest in the central cup of the objective, it may in passing over the convex surface of the objective be caught in one of the series of recesses or depressions designed to hold the ball and thus exact a penalty against the player.

The preferred form of my invention is illustrated in the accompanying drawing in which

Fig. 1 is a plan view of my invention;

Fig. 2 is a vertical section of the same taken on the line 2—2 of Fig. 1;

Fig. 3 is a plan view of the blank sheet used for forming one vane;

Fig. 4 is a plan view of the blank sheet for the complementary vane, and

Fig. 5 is a schematic diagram illustrating one game in which the invention may be used.

Specifically my invention provides a convenient and effective objective for the playing balls. I make it in the form of a convex disk 6. This may be of relatively soft sheet metal or compositions of wood, fiber, pulp, plastics or the like. This disk rests upon the peripheral edge with its convexity upward as shown in Fig. 2. The center portion of the disk 6 is formed as a depression or cup 7 of suitable depth and width to hold the playing ball 8 if the same rolls into the cup without too great momentum.

The center of the cup has an opening which holds a post 9. This is of metal or similar mate-

rial and is upset or riveted in the opening of the disk so that the post 9 stands vertically. An intermediate portion 10 of the post is narrowed or cut away as shown in Fig. 2 for the purpose which will appear subsequently.

The upper portion of the post has an internal screw-threaded recess in which a staff or roll 11 is screwed. This staff carries a guidon 12 or similar marking flag. This is used where a succession of the objective units are used in the game.

In the convex upper surface of the disk 6, and equally spaced around the cup 7 are recesses 13 slightly larger than the playing ball 8. These recesses have accentuated slopes on the sides toward the cup while the opposite side of the disk is struck up above the surface of the disk to form a ridge 14. This increases the depth of the recess and serves the dual purposes of holding the ball rolling down the declivity or repelling one which is travelling in the direction toward the center cup 7.

I have shown three recesses 13 equally spaced but the number may be increased or decreased as desired.

An added hazard or handicap in the game is afforded by means of vanes which extend radially from the post 10 and divide the cup 7 into compartments. One vane 15 is formed of a blank of sheet material shown in Fig. 4. Centrally it is slotted as at 16. The blank in its final position is wrapped around the center post 10 in contact with the wide upper portion of the latter. The ends of the blank are then brought together as shown in Fig. 1. A second or complementary vane 17 is shown in Fig. 3. This vane is cut away at the center to provide a narrow band 18. The narrow band 18 is designed to fit in the slot 16 of the vane 15 and be wrapped around the narrow portion of the post 10 as indicated in Fig. 2. The ends of the vane 17 extend radially and at an angle of 120 degrees. This serves to bring the band 18 against the ends of the slot 16 and thus hold the ends of vane 15 in a mid-position between the ends of the vane 17. Since the band 18 is beneath the broad portion of the post 10, the vanes are prevented from accidental dislodgment from the post 10.

Preferably the vanes 15 and 17 extend between the rings 13 but may be shifted to vary the conditions of the game.

In Fig. 5, I have shown one of numerous arrangements which may be made of the game apparatus. Here the several units or ball re-

ceivers are arranged in one line spaced from each other and distinguished from each other by different numbered marking staffs 11. There are as many playing balls 8 as there are players. Each player starts from a given point and rolls his distinctive numbered ball 8 toward the first receiver or disk. The ball may come to rest near the receiver in which case the turn passes to another player. If the ball lodges in the cup 1 it may then be played from that point toward the second receiver and the play continues until the player fails to land the ball in the next cup.

The play then passes to the next player. He may continue playing for the receivers in succession but in addition may digress to strike his opponent's ball. The latter is then forced to return to the starting point while the player may continue.

If, however, the ball fails to remain in the cup 1 but strikes the abutment vanes 15 and 17, it may bounce out and roll back into a depression 13. In this case the ball must again be played from the starting point at the player's next turn. Suitable rules can be made governing fouls and the arrangement of the receiving disks may of course be varied at will.

While I have illustrated the preferred form

of my device, the invention itself is limited solely by the scope of the appended claims.

What I claim is:

1. A unitary receiver for playing balls comprising a disk having a generally convex upper surface, a cup centrally formed in the disk and a series of generally oval ball-receiving recesses spaced circumferentially on the convex surface of the disk between its edge and the cup.

2. A unitary receiver for playing balls comprising a disk having a generally convex upper surface, a cup centrally formed in the disk, a vertical post in the center of the disk, a slotted vane clamped around the post, a second vane having a reduced central portion passing through the slotted vane and clamped to the post.

3. A unitary receiver for playing balls comprising a disk having a generally convex upper surface, a cup centrally formed in the disk, a vertical post in the center of the disk, said post having a narrowed middle portion, a slotted vane clamped around the post, a second vane having a reduced central portion passing through the slotted vane and clamped to the narrow middle portion of the post.

FRANCISCO P. GOROSPE.
